WASHING MACHINE

Matthew L. Kelly, Philadelphia, Pa., assignor to
The Insinger Company, Philadelphia, Pa., a
corporation of Pennsylvania

Application May 29, 1930, Serial No. 457,299

4 Claims. (Cl. 141—9)

This invention relates to a washing machine primarily adapted for the washing and rinsing of dishes or the like.

It is primarily aimed to provide a construction wherein washing and rinsing may take place within the same chamber or tank without admixture of the washing and rinsing fluids or loss of any of the washing fluid.

Another object is to provide a construction whereby a novel means is employed above the washing fluid for movement to different positions to properly direct the flow of the fluids used, according to whether the same is a washing fluid or a rinsing fluid.

Another object is to provide means whereby the fluid-directing or controlling means is actuated through actuation of the control valves used for the washing and rinsing fluids.

Various additional objects and advantages will become apparent from a consideration of the description following taken in connection with accompanying drawings illustrating one exemplary embodiment.

In said drawings:—

Figure 1 is a view of the machine partly in end elevation and partly in section;

Figure 2 is a view of the machine, partly in side elevation and, partly in longitudinal section;

Figure 3 is a fragmentary end elevation to particularly show the operating mechanism for the tilting plate;

Figure 4 is a horizontal sectional view taken on the line 4—4 of Figure 1;

Figure 5 is a fragmentary longitudinal sectional detail illustrating the mounting of the strainer trap for the washing fluid, and

Figure 6 is a perspective view of the mounting rod for the tilting plate.

Referring specifically to the drawings, wherein like reference characters designate like or similar parts, 10 indicates a conventional stand which supports a washing tank or receptacle 11 on which is surmounted a hood 12. Said hood 12 is open at opposite ends at 13 in order that trays 14 adapted to contain the dishes 15 or other articles to be washed, may be freely inserted and removed, such tray being of skeleton or conventional form. The sides of the tank 11 adjacent the top, are extended outwardly at portions 16 and the hood 12 has flanges 17 directly engaging the upper ends of the wall portions 16 which are secured thereto in any suitable manner. Suitably fastened within the hood to the flanges 17 and against side wall portions 18, are angles 19 which serve

are adapted to be pushed or pulled. The end portions 20 of the tracks 19 preferably incline upwardly, as shown in Figure 2, and the bottom walls 21 of the extensions 22 at the openings 13, also, preferably, incline upwardly at the same angle.

The tank 11 is adapted to contain a suitable washing fluid, usually water, having chemicals or detergents therein, and such washing fluid is adapted to be withdrawn from the tank through a pipe 23 in communication with the tank 11, through the action of a pump 24 with which said pipe communicates and which pump is supported, for example, on a shelf 25 forming part of the stand 12. The pump 24 may be operated from any suitable source of power and usually, is operated by an electric motor 26 which may be coupled to the shaft 27 of the pump 24 and supported on the said shelf 25. The pump discharges the water with admixed chemicals or detergents through a pipe 28, which is preferably vertically arranged. Extending laterally from the pipe 28, are manifolds 29 and 30, the former extending into the hood 12 above the basket 14 and the latter extending into the tank below the basket 14. Projecting horizontally from the manifolds 29 and 30, are distributing pipes 31 and 32, respectively, the former having discharge orifices 33 in the lower portion thereof, and the latter having discharge orifices 34 in the upper portion thereof, whereby the washing fluid is projected onto the dishes 15 both from above and from below.

At the base of one of the wall portions 16, within the tank 11, a foraminous or strainer tray 35 is removably disposed, resting, for instance, on lugs 36 integral with the tank 11 and at its ends resting on inclined surfaces 37 and lugs 38 also integral with the tank 11. During the discharge of washing fluid onto the dishes 15, a tray or plate 39 is tilted so as to rest on the inner edge of the tray 35 and as a result, the falling washing fluid strikes the tray 39, which is imperforate, and flows into the strainer 35, which removes solid particles therefrom, the detergent returning to the supply in the tank 11, through the perforations of the tray or strainer 35, so that it may be again pumped onto the dishes in a continuous cycle of operation.

The plate or tray 39 is carried by a rock shaft 40 which may be square as at 41 throughout the major portion of its length. Cleats 42 may surround the squared portion 41 of the rock shaft and be secured to the plate 39 in order to rigidly fasten it to the rock shaft. At opposite ends, 55

plate or tray 39 may have upstanding flanges 43 to prevent fluid from overflowing adjacent edges thereof. Through actuation of the rock shaft 40, the plate or tray 39 may be moved from engagement with the tray 35 into engagement with a trough 44, in which position it is disposed at the opposite inclination to that which it assumes when engaging tray 35, as shown in full lines in Figure 1. Trough 44 is in communication with a drain pipe 45 which extends to one end of the tank 11, thence under such tank and leading to a sewer or other point of discharge. A vertical pipe 46 rises from the pipe 45 and extends through a water-tight connection 47 into the tank 11. Pipe 46 is open at the top and constitutes an overflow or scum-removing means with respect to the washing fluid.

The pipe 28 has valves 48 and 49 located therein, one of which is adapted to be open while the other is closed, and vice versa. The upper end of pipe 28 communicates with a source of rinsing water supply, which may be a city service line of water or otherwise. When the valve 49 is open, rinsing water as it cannot pass the valve 48, will discharge through the orifices 33 and 34 in order to rinse the dishes, and will fall onto the plate 39 and flow into the trough 44 and from the same discharge through pipe 45 into the sewer or the like. However, when the valve 49 is closed, the valve 48 is open, and the pump 24, which was inactive during the rinsing operation, will pump washing fluid from the tank 11 through the various pipes and discharge the same through ports 33 and 34 against the dishes. During the washing operation, the plate 39 will be inclined opposite to the position shown in Figures 1 and 3 and hence, will cause the washing fluid to flow through the strainer 35 and return to the tank.

Valve 49 is manually operated by a handle 50. A similar handle 51 controls valve 48. A pitman 52 is pivoted to both valve handles 50 and 51. The operation of the valves 50 and 51 causes simultaneous operation or shifting of the plate 39 so that the latter will be at the proper angle to discharge into tray 35 or trough 44 according to whether or not washing fluid or rinsing water, respectively, is flowing. To this end, rock shaft 40 has trunnions 53 at its ends which are suitably journaled in the end walls of the tank in a manner to permit removal of the rock shaft, when desired, and a crank 54 is removably and rigidly fastened to one of the trunnions 53 outside of said tank 11. A pitman 55 is pivoted at 56 to crank 54 and is pivoted at 57 to the handle 51.

To briefly recapitulate, with the parts shown as in Figure 1, valve 48 is closed and valve 49 is open and motor 26 is not in operation. Accordingly, rinsing water flows through pipe 28, manifolds 29 and 30 and pipes 31 and 32, discharging upwardly and downwardly against the dishes 15 through the orifices 33 and 34. The falling water strikes plate 39 and flows therefrom into trough 44, passing from the latter through pipe 55 to the sewer or other point of discharge. While this operation of rinsing the dishes is transpiring, the rinsing water is effectively prevented by the plate 39 and trough 44, from flowing into the tank 11 proper, and hence, it will not disturb or admix with the washing fluid contained in the latter.

In order to wash the dishes, either valve handle 50 or 51 or pitman 52 is raised, thus opening valve 48 and closing valve 49. Thereupon, with the motor 26 in operation, pump 24 through pipe 23, withdraws washing fluid from the tank 11 and discharges it through pipe 28, manifolds 29 and

30, pipes 31 and 32 from which it travels in opposite directions against the dishes through the orifices 33 and 34. The aforesaid movement of closing valve 49 and opening valve 48 moves pitman 55 which rocks crank 54 and shaft 40, accordingly, tilting the tray or plate 39 from the angle shown in Figure 1 to its opposite angle where it rests on the tray 35. In the latter position, plate or tray 39 catches the falling detergent and directs it through strainer 35 back into the tank 11, for re-use or continuous cycling through the action of pump 24.

By reason of the described construction, I am enabled to produce a washing machine having a single tank accommodating both rinsing and washing operations without necessitating the discard or loss or weakening of washing solution, the detergents or chemicals of which are expensive.

Various changes may be resorted to provided they fall within the spirit and scope of the invention as defined by appended claims.

I claim:

1. In a machine of the class described, a tank to contain a washing fluid, conduit means leading from the tank including a pump to withdraw fluid from the tank and return it thereto over articles to be washed, a plate spaced above the bottom of the tank in the line of return of said fluid, means spaced above the bottom of the tank mounting said plate for tilting to one position to direct said fluid into the tank and for oppositely tilting the plate, a drain spaced above the bottom of the tank to which rinsing water is directed by the plate in its last mentioned position, whereby the tank is substantially unobstructed from side to side across the bottom to increase the area which accommodates the washing fluid, the said conduit means having a connection for the supply of rinsing water through the discharge portion thereof, valve means to cut off the supply of rinsing water through the discharge portion, valve means in said conduit between the pump and said discharge portion to prevent the passage of rinsing water to the pump, and mechanism connecting the second mentioned means and both valve means to open one valve means as the other valve means is closed and vice versa and whereby the plate is operable automatically with both valve means and vice versa.

2. In a machine of the class described, a tank to contain a washing fluid, conduit means including a pump to withdraw fluid from the tank and return it thereto over articles to be washed, a tiltable plate spaced above the bottom of the tank in the line of return of said fluid, means for tilting said plate to direct said fluid into the tank and for oppositely tilting the plate means spaced above the bottom of the tank mounting said plate, opposite side walls of the tank spaced above the bottom of the latter having offset portions on the interior of the latter, a trough-shaped drain engaging one offset portion to which rinsing water is directed by the plate in its last mentioned position, a trough-shaped screen member engaging the other offset portion into which washing fluid is directed to the tank in the other position of the plate, opposite edge portions of said plate in its respective positions overlapping said drain and screen member.

3. In a machine of the class described, a tank adapted to contain a washing fluid, means operable to pump said washing fluid into engagement with articles disposed within the tank, a pipe connected to said means through which rins-

- ing water is supplied to the articles, a trough in said tank above its base for the discharge of rinsing water, a plate tiltably mounted in the tank in the line of discharge of the washing fluid and rinsing water to discharge washing fluid into the tank in one position and to discharge rinsing water into the trough in another position, a control valve for the first mentioned means and a control valve for said pipe, means connecting said valves so that one will be opened as the other is closed and vice versa, and a linkage connection from the last mentioned means to the plate to tilt the plate to and from its two positions through operation of said valves.
4. In a machine of the class described, a tank, said tank being adapted to contain a washing fluid, a strainer in said tank at one side thereof, a trough in said tank at the other side thereof for discharge purposes, a plate tiltably mounted in the tank of greater width than the distance between the strainer and trough for movement-limiting engagement with either said strainer or said trough to discharge into the same, means above the plate to support articles, means whereby said washing fluid may be pumped into engagement with the articles and whereby rinsing water may be supplied to the articles, control valves for the last mentioned means, said plate being in the line of discharge of the washing fluid and rinsing water, means connecting said valves so that one will be opened as the other is closed, and a linkage connection from the last mentioned means to the plate to tilt the plate through operation of said valves.
5. In a machine of the class described, a tank, said tank being adapted to contain a washing fluid, a strainer in said tank at one side thereof, a trough in said tank at the other side thereof

MATTHEW L. KELLY.
